UNITED STATES PATENT OFFICE.

GLENN D. MITCHELL, OF COLLEGE POINT, NEW YORK, ASSIGNOR, BY MESNE ASSIGNMENTS, TO L-W-F ENGINEERING COMPANY, INC., OF COLLEGE POINT, LONG ISLAND, NEW YORK, A CORPORATION OF NEW YORK.

STRUT CONSTRUCTION.

1,353,538.

Specification of Letters Patent. Patented Sept. 21, 1920.

Application filed March 21, 1917. Serial No. 156,289.

To all whom it may concern:

Be it known that I, GLENN D. MITCHELL, of College Point, in the county of Queens and in the State of New York, have invented 5 a certain new and useful Improvement in Strut Construction, and do hereby declare that the following is a full, clear, and exact description thereof.

My invention relates particularly to strut 10 constructions which may be used on aeroplanes but which are capable of being applied to other similar structures.

The object of my invention is to provide 15 a strut construction of the proper shape, as for example, in streamline form, but which is made hollow so that the ends of the strut may be attached to the remainder of the structure, thus avoiding the presence of the external fittings, which cause additional 20 wind resistance.

A further object is to provide a construction 25 of this character in which the end of the strut is strengthened on the interior at the point where it is attached to the re- mainder of the structure.

A further object is to provide an internal 30 fitting for the strut which is so arranged that the strut may be located at any suitable angle to the remainder of the structure 35 without interfering with the position of the fitting.

A further object is to provide a fitting for 35 this purpose which is so applied to the end of the strut that the strut and the fitting are capable of being readily attached to the 40 different portions of the aeroplane, or other structure, in which the strut is used.

Further objects of my invention will appear 45 from the detailed description thereof contained hereinafter.

While my invention is capable of embodiment 50 in many different forms, for the purpose of illustration I have shown only certain forms thereof, in the accompanying drawings, in which

Figure 1 is a perspective view of a strut 55 shown as applied to a portion of an aeroplane in accordance with my invention;

Fig. 2 is a vertical section of a strut alone; 60 Fig. 3 is another vertical section of the same taken in a position at right angles to the position of the section in Fig. 2;

Fig. 4 is a similar view to Fig. 3, showing the strut attached;

Fig. 5 is a similar view to Fig. 2 showing the strut attached;

Fig. 6 is a perspective view showing the plate located at the rear edge of the strut for attachment to one of the bracing wires;

Fig. 7 is a perspective view of one of 60 the washers used at the front of the strut;

Fig. 8 is a side elevation of one of the plates used at the side of the strut;

Fig. 9 is a front elevation showing the method of attaching the overhang strut; 65 and

Fig. 10 is an elevational view taken parallel to the side of the overhang strut.

In the drawings I have shown a beam 1 supporting upon the top thereof a strut 2 70 made of sheet metal, as for example steel, in such a manner that at the rear edge there is provided a welded joint 3. In the interior of the strut 2 there is a reinforcing plate 4 having upwardly directed wings 5 and 6 and 75 downwardly directed semi-circular ears 7 and 8, at the sides thereof, which are welded or secured in any suitable manner to the interior of the strut 2. The ears 7 and 8 are provided with perforations 9 and 10 which 80 register with corresponding perforations 11 and 12 in the sides of the strut 2. By providing the upwardly directed wings 5 and 6 they may be readily conformed to the internal surface of the strut 2, and furthermore, 85 the greatest strength is obtained at the central portion of the strut immediately over the openings 9 and 10 where the fastening of the strut to the remainder of the structure takes place. Further, by providing the 90

downwardly directed ears 7 and 8, the front and rear portions of the reinforcing plate 4 are located some distance above the end of the strut 2 so that the end of the strut may be cut at an angle to fit the strut to the position of the part to which it is attached without necessitating any change in the form of the reinforcing plate 4. Furthermore, the curved lower ends of the ears 7 and 8 assist in the accomplishment of the same purpose 100 (See Fig. 2).

In the interior of the strut 2 adjacent to the ears 7 and 8 are located washers 13 and 13^a. Adjacent the washers 13 and 13^a are lo-

cated the ends of a U-shaped plate 14, the lower portion of which is welded to a supporting plate 15. A bolt 16 is adapted to pass through the holes 17 and 18 in the upper portions of the U-plate 14 and through the holes 9, 10, 11 and 12 as well as the washers 13 and 13^a. A nut 19 may be provided for the bolt 16. The plate 15 has four holes 20 at its corners to receive two U-bolts 21, 22, which pass downwardly around the beam 1, so that their ends may be fastened together under the beam 1 by means of plates 23 and 24 which pass over the ends of the U-bolts 21 and 22 and are secured thereon by means of washers 25 and nuts 26. Above the plate 15 at the front of the beam 1 the U-bolts 21 and 22 pass through washers 27 and at the rear said U-bolts pass through holes 28, 29 in a triangular plate 30 having a hole 31 to receive a suitable fastening 32 for a bracing wire 33, having a turn buckle 34 for tightening the same. At the side of the strut 2 one or both of the U-bolts 21 and 22 may receive a strap of metal 35 folded on itself so as to engage with suitable fastenings 36, 37 for bracing wires 38, 39 provided with turn buckles 40, 41. As shown in Figs. 9 and 10 the U-bolts such as 21 and 22 also provide means for securing thereto a strut directed outwardly and laterally at the side of the aeroplane. The strut shown in these figures is attached to a U-bolt 42 by means of a strap of metal 43 secured to the strut in the same manner as the U-plate 14. In this instance, however, I locate between the upper ends of the strap 43 and over the bolt 16 a short tube 44.

While I have described my invention above in detail, I wish it to be understood

that many changes can be made therein 40 without departing from the spirit of my invention.

What I claim is:

1. In combination, a hollow strut, a fitting lining one end thereof, a base member extending within said end, and a connection between said fitting and said base member, said connection being within the interior of said strut. 45

2. In combination, a hollow strut, a fitting lining one end thereof, a base member extending within said end, and a securing bolt extending through said fitting and said attaching member within the interior of the strut. 50

3. A hollow strut having a reinforcing fitting lining one end thereof, portions of the outer end of said fitting being disposed inwardly of the end of the strut, so as to leave unreinforced portions of the strut adjacent its end which may be readily cut away to conform to the desired angular position of the strut. 55

4. In combination, a hollow strut of streamline form, a hollow fitting lining one end thereof and having ears projecting toward the end of the strut, so as to leave said end unreinforced except for such ears, a base member extending within said strut, and a bolt extending through the strut, ears and 60 base member. 70

In testimony that I claim the foregoing I have hereunto set my hand.

GLENN D. MITCHELL.
